(57) **CLAIM**

The ornamental design for a water dispenser universal filtration tank, as shown and described.

DESCRIPTION

FIG. 1 is a front perspective view of a water dispenser universal filtration tank, which illustrates in phantom lines a view of a cap valve;

FIG. 2 is a front plan view of the tank of FIG. 1;

FIG. 3 is a right side elevation view of the tank of FIG. 1;

FIG. 4 is a top plan view of the tank of FIG. 1;

FIG. 5 is a bottom plan view of the tank of FIG. 1; and, FIG. 6 is a front perspective view of the tank of FIG. 1, illustrating an exploded view of the component pieces comprising the tank.

The phantom lines showing a cap valve are for illustrative purposes only and form no part of the claimed design.
